SOUND RECORDING AND REPRODUCING

Guy Clutier, Paris, and Marc Assada,
Villefranche-sur-Saone, FranceApplication September 2, 1947, Serial No. 771,660
In France September 9, 1946

6 Claims. (Cl. 179—100.3)

1

It has already been proposed to obtain a so-called "sound relief" effect for improving the grade of a moving picture show by providing in the projecting hall a so-called sound environment or sound atmosphere which is obtained by producing ground noises through suitably placed loud-speakers.

Now, all the means disclosed theretofore for obtaining this result are promised to failure inasmuch as these means require a deep transformation of the cinematographic films themselves, as also of the recording and reproducing apparatuses. As a matter of fact, one of the means which are the most readily apparent to the mind consists in providing on the film one or more supplementary sound tracks for energizing the means which are to produce the sounds atmosphere and this leads to a transformation of the apparatuses operating with such films.

Our invention allows a very easy solving of the problem of the automatic control of a sound atmosphere without it being necessary to modify in any manner whatever either the films or the view taking means, the sound recording means or the projecting and sound producing means existing nowadays.

The method forming the basis of the invention is remarkable chiefly through the fact that, on one hand, there is provided on at least one side of the film, in addition to the usual picture area and sound track, a further separate track for controlling the sound atmosphere. We will call hereinafter this supplementary track a "pilot track" and it may be provided on the part of the film carrying the perforations which latter do not trouble operation if sufficient care is exercised as is amply shown by experience; on the other hand, according to said methods, said pilot track cooperates with a light box and with a photocell controlling a preliminary pilot amplifier the input of which is modulated by the usual sound reading means, said amplifier energizing either a discriminator provided with two outputs modulating, in the desired proportion as defined by the pilot track, the usual system including the amplifier and screen loud-speakers and a separate system including an amplifier and a sound atmosphere loud-speaker or else said pilot amplifier energizes a selector system located at the output of the usual amplifier.

The pilot track may be of the constant density, variable breadth type or else of the variable density type with a constant breadth or again it may be of the variable frequency type for removing any sensitivity of the system to dust,

scratches, oil deposits or the like soiled parts of the film.

Our invention has also for its object the execution of a device for drawing the pilot track on a standard sound track, said device being remarkable in particular through the fact that it includes means for drawing a track with a variable breadth and constant density under the control of a relay that is in its turn controlled by hand by an operator entrusted, before public projection, with the preparation of the film providing a sound atmosphere.

Another object of our invention consists in executing an arrangement for reading a pilot track, which arrangement is remarkable in particular by the fact that it includes a photoelectric reading system with a photocell and an energizing lamp, and a pilot amplifier directing towards the different loud-speakers in the hall the modulation produced by the usual sound track of the film, said pilot amplifier being adapted to this purpose to control differentially either the input into a plurality of amplifiers of the output of the usual amplifier, the pilot amplifier acting in any case after the manner of a switch.

Our invention covers also by way of a new article of manufacture the sound film including a pilot track serving for the execution of an automatic sound atmosphere.

30 The above referred to means allow obtaining the most varied sound atmosphere effects such as the noise of a crowd, sound travelling, a panoramic sound view, noise from beyond the screen, stereoscopic noises etc.

35 In the case where the pilot track is of the variable frequency type, the arrangement serving for incorporating it to the film may consist in inking wheels the peripheries of which are provided with inking teeth arranged at intervals that vary according to the wheels considered, said wheels being brought separately into contact with the film by the operator entrusted with the production of the pilot track.

40 The photoelectric reader for the variable frequency pilot track controls through the agency of a rectifying amplifier a relay provided with a plurality of vibrating blades each of which is tuned to a predetermined pilot frequency and controls the circuit of a loud-speaker or group of loud-speakers associated with the screen and/or the means for producing the sound atmosphere.

45 Screening means are furthermore provided for cutting off, in register with the perforations of the film, the light bundle serving for the ener-

gization of the cell controlling the means producing the sound atmosphere.

Said screening means are preferably constituted by a toothed drum containing the lamp energizing the photocell controlling the sound atmosphere and showing at the points corresponding to the intervals between the perforations in the film openings for the passage of the energizing light bundle acting on the cell considered.

Means for gradually energizing the loud-speakers are inserted in the circuits feeding same to prevent said loud-speakers from being started too abruptly. Said gradually energizing means are preferably constituted by a rocking mercury rheostat.

Further features and objects of our invention will appear in the reading of the following description, given out by way of example, of certain embodiments without same forming in any manner a limitation to our invention. Said embodiments are illustrated in accompanying drawings wherein:

Fig. 1 is a general diagram of the arrangement including means for drawing the pilot track and a system for producing the sound atmosphere and the sound at the screen.

Fig. 2 is a diagrammatic perspective view of the track drawing means and of the reading means for the track producing the sound atmosphere or pilot track, together with a part of the sound film and pilot track.

Fig. 3 is a diagrammatic view, partly in perspective, of a modification of the means producing the pilot track.

Fig. 4 is a diagrammatic view of a modification of a photo-electric reader for the pilot track.

Fig. 5 is a rough diagram of a pilot amplifier.

Fig. 6, 7 and 8 show three half-sections of a sound film carrying pilot tracks for three different frequencies.

Fig. 9 illustrates the recording means for a track with three pilot frequencies.

Fig. 10 is a cross-section of the screening means for the driving perforations of the film.

Fig. 11 is a perspective view of a relay with three vibrating blades.

Fig. 12 illustrates an arrangement for the gradual feeding of one of the loud-speakers.

Lastly Fig. 13 is a diagram illustrating a rectifying amplifier with the auxiliary parts of the means producing the sound atmosphere.

In Fig. 1, we have shown at 1 the cinematographic projecting apparatus with its upper and lower film holders 2 and 3, at 4 the photocell of the usual sound reader, at 5 the light box enclosing the lamp energizing the cell 4 and at 6 the sound film with its perforated edges 6' and 6'', the usual sound track 6''' and the area carrying the photographic pictures 6'''.

The photocell 4 is connected with the input of the pilot amplifier 7 including two outputs modulating on one hand the normal screen amplifier 8 feeding the screen loud-speaker or loud-speakers 9 and on the other hand a special amplifier 10 feeding the loud-speaker or loud-speakers 11 producing the sound atmosphere.

Beyond the usual sound reader 4—5 is provided a system including means 12 for drawing the pilot track and a reader for said pilot track constituted by a photocell 13 with its light box 14 containing the corresponding energization lamp.

The cell 13 is connected with the pilot amplifier 7 adapted as disclosed hereinafter to control in opposite directions the modulation applied to the

normal amplifier 8 and the modulation applied to the sound atmosphere amplifier 10.

In order to execute the pilot track on film 6, it is possible as shown in Fig. 2 to make use of drawing means including a drawing pen 15 of a variable spacing constituted by a stationary arm 15' and a movable arm 15'' pivotally secured at 15''' to said stationary arm, the interval between the arms being fed by the ink container 16.

The movable arm 15'' is connected through a rod 17 with a plunger core 18 held normally in equilibrium between two stationary coils 19 and 20 the windings of which are connected with the common terminal of the direct current supply and with one of the two ends 22' and 22'' of a potentiometer 22, the brush 23 of which is connected with the other terminal of the current supply considered.

The location of the inking pen nose 15 is adjusted so as to come into contact with the film 6 along one of the perforated edges of the latter, say 6''.

This track drawing means operates as follows: for preparing the film before public projection thereof, the operator entrusted with the drawing of the pilot track begins by projecting normally said film and controls the handle of the brush 23 with a view to measuring the modulated power feeding the loud-speakers for the screen on one hand and for the sound atmosphere on the other, the energy fed to said sets of loud-speakers being as disclosed hereinafter provided in opposite directions.

The operation of the brush 23 produces a more or less considerable spacing between the arms of the drawing pen 15 that draws on the perforated marginal area 6'' of the film 6 a line forming the pilot track 25.

The result of this drawing is immediately ascertained by the operator who in case of any defect or error in estimation may at least wipe away the part of the pilot track that is not satisfactory and begin the operation over again. As a matter of fact, the reader of the pilot track that energizes the pilot amplifier is located immediately beyond the drawing means. In Fig. 2, it is immediately apparent that 13 designates said reader for the pilot track and 14' is the lamp energizing said cell through the condenser 26 and the slotted screen 27.

As apparent from Fig. 3, the reader of the pilot track may be of the reflecting type including a light box 14a with the lamp 14', a condenser 26a, a mirror 27a and a photocell 13a in its casing 28.

The means drawing the pilot track may also be executed as illustrated in Fig. 4. In this form of execution, the drawing means 29 which is of a rotary type includes two sectors 29' and 29'' connected with one another along a radial line and forming a variable angle with reference to one another, the feeding with ink being obtained through a container 16'. The angular position of the drawing means 29 is controlled by a spindle 30 with which it is rigid and on which is secured the rotor 31 of the motor 32 of which the field or stator 33 is fed by a source of direct current controlled through a rheostat that is not illustrated and that may be controlled by the operator who has to draw the pilot track.

The pilot amplifier 7 replacing the usual preliminary cell amplifier, modulating the power amplifier of the screen loud-speakers, comprises a modulation input connected with the photo-

cell 4 of the usual reader of the sound track 6''' and an input for controlling the production of the sound atmosphere, connected with the cell 13 of the reader of the pilot track 25. The cell 4 energizes through the agency of an amplifying tube 34 the two modulating grids mounted in parallel of two octode tubes 35—36 modifying the depth of modulation through a modification of the voltage applied to each suppressor grid under the control of the pilot cell 13; the anodes of these two octodes feed directly the screen amplifier 8 and the amplifier for sound atmosphere 10. The cell 13 energizes through the two amplifying tubes 37 and 38 two symmetrical chains including, the former an amplifying tube 39 and a detecting tube 40 controlling the voltage of the suppressor grid in the tube 35 while the second chain includes an amplifying tube 41 and a detecting tube 42 controlling the voltage of the suppressor grid of the tube 36, the grid bias in the two detecting tubes 40 and 42 being different from one another.

The depths of modulation collected at the output of each tube 35 and 36 vary thus in opposite directions with reference to one another under the control of the pilot cell 13.

In Figs. 6 to 8 the pilot-frequency track of variable frequency 41 includes an opaque line of constant width throughout the solid portions separating the perforations of the film 42. According as to whether the track is produced throughout all the intervals separating the perforations (Fig. 6) or only over one interval out of two (Fig. 7) or one interval out of three (Fig. 8), the pilot track of a standard sound film advancing at the rate of 96 perforations per second will produce a frequency of 96, 48 or 32 periods per second. Of course it is possible to provide any desired frequency underneath 96 periods per second.

In order to execute the recording of such a pilot track, it is possible to use an inking device of the type illustrated in Fig. 9 and including three wheels 44a, 44b and 44c dipping into an ink bath contained in a vat 43. Said wheels are provided with inking teeth distributed over the periphery of said wheels at different intervals for producing on the film 42 traces or impressions 41 at different spacings as disclosed hereinabove.

The inking wheels 44a, 44b and 44c may be controlled by electromagnets 45a, 45b and 45c the circuits of which are controlled by the operator entrusted with the formation of the pilot track.

The reader of the pilot track of variable frequency comprises as shown at Fig. 10 a toothed drum 46 the teeth of which engage the perforations 42a of the film 42; said drum is provided between its teeth with ports 47 allowing the passage of the light beam sent out of the light source 48 arranged inside said drum and serving for the energization of the photocell 49 solely at the points corresponding to the intervals between the perforations of the film.

Under such conditions, the photocell 49 may be energized only if the above intervals between the perforations are not provided with any pilot impressions.

As apparent from Fig. 13, the cell 49 feeds a rectifying amplifier 50 including a low-pass filter 51 eliminating the frequencies above 100 periods per second.

The rectifying output tube of the rectifying amplifier energizes a relay 52 (Figs. 11 and 13) provided with a plurality of vibrating blades (three in the example illustrated), tuned to the

pilot frequencies say the frequencies of 96, 48 and 32 periods per second in the case of the choice of frequencies considered hereinabove.

Each of the vibrating blades 52a, 52b and 52c controls means 53 for the gradual energization of the loud-speaker 54 either for the picture screen or for the means producing the sound atmosphere.

The arrangement 53 referred to (Figs. 12 and 13) includes a relay 53a the circuit of which is controlled by the corresponding vibrating blade 52a and the vane 53b of which provides for the rocking of a mercury rheostat formed by an arcuate tube 53c enclosing a drop of mercury 53d, wherein is located a main electrode 53e and a certain number of auxiliary electrodes 53f interconnected through resistances 53g.

As long as the electromagnet relay 53a is not energized, the tube 53c slopes towards the right and the drop of mercury 53d lies on the right hand side thereof. As soon as the relay is energized the tube 53c slopes towards the left and the drop of mercury is displaced towards the left in a fraction of a second while it establishes the contact between the electrode 53e and the electrode 53f so as to short-circuit in succession the resistances in series 53g. The loud-speaker 54 is thus started without any jerks and in a gradual manner.

It is apparent that with the improved arrangement disclosed hereinabove the screen and the sound atmosphere loud-speakers are fed with modulated current in a manner that is perfectly independent of the imperfections of the pilot track, which imperfections may be due for instance to wear.

Obviously the examples of execution of the above described arrangements as illustrated in accompanying drawings have been given out merely by way of exemplification and many detail modifications may be brought thereto without unduly widening the scope of the invention. Thus it is possible to provide two pilot tracks controlling a sound equipment for the screen and two equipments for sound atmosphere; it is also possible to provide for the drawing of the pilot track on a separate strip forming a control strip for the sound atmosphere, that is unwound in synchronism with the sound film inside an apparatus that is separate from the extent projecting means. Similarly it is possible to mount at the output of the pilot amplifier a mechanical selector for the modulated energy produced by the usual amplifier.

What we claim is:

55. Arrangement for drawing on a sound film at least one pilot track comprising in combination means for transporting said sound film along a predetermined path; a vat adapted to contain a liquid capable of recording said pilot track, said vat arranged near the path of said film; a plurality of toothed wheels each having its teeth arranged at different spacings and arranged so as to dip into liquid in said vat; axles carrying said toothed wheels movably toward and away from said predetermined path of said sound film; magnetic cores mechanically connected with said axles of said toothed wheels; coils adapted to control said magnetic cores so as to move the teeth of said wheels into engagement with said sound film, when energized; and means for selectively connecting said coils to a source of electric current.
60. Arrangement for drawing on a sound film at least one pilot track comprising in combination means for transporting said sound film along a predetermined film path; a plurality of toothed
65. Arrangement for drawing on a sound film at least one pilot track comprising in combination means for transporting said sound film along a predetermined path; a vat adapted to contain a liquid capable of recording said pilot track, said vat arranged near the path of said film; a plurality of toothed wheels each having its teeth arranged at different spacings and arranged so as to dip into liquid in said vat; axles carrying said toothed wheels movably toward and away from said predetermined path of said sound film; magnetic cores mechanically connected with said axles of said toothed wheels; coils adapted to control said magnetic cores so as to move the teeth of said wheels into engagement with said sound film, when energized; and means for selectively connecting said coils to a source of electric current.
70. Arrangement for drawing on a sound film at least one pilot track comprising in combination means for transporting said sound film along a predetermined film path; a plurality of toothed

wheels arranged along said predetermined film path; and each having printing teeth arranged at different spacings for printing said pilot track; means supporting said toothed wheels independently of each other and movable between inoperative position spaced from said sound film and operative position in engagement with said sound film; printing said pilot track on the same; and manually operable means for selectively moving said toothed wheels from inoperative into operative position, whenever desired.

3. An arrangement for drawing on a previously developed sound film having a sound track at least one pilot track comprising in combination means for transporting said sound film along a predetermined path; sound reproducing means for reproducing the sound recorded by said sound track; at least one pilot track producing member arranged along said predetermined path; means supporting said pilot track producing member movable between inoperative position spaced from said predetermined path and operative position moved toward said predetermined path in engagement with a sound film passing along the same so as to be adapted to produce a pilot track on the same; manually operable actuating means for moving said pilot track producing member from inoperative into operative position, whenever desired; photoelectric means arranged along said predetermined path after said pilot track producing member so as to create electric current variations corresponding to variations of the pilot track produced by said pilot track producing member; and means for varying the sound reproduced by said sound reproducing means in accordance with said electric current variations.

4. An arrangement for drawing on a previously developed sound film having a sound track at least one pilot track comprising in combination means for transporting said sound film along a predetermined film path; sound reproducing means for reproducing the sound recorded by said sound track; a vat adapted to contain a liquid capable of recording said pilot track; said vat arranged near the path of said film; a plurality of toothed wheels each having its teeth arranged at different spacings and arranged so as to dip into liquid in said vat; axles carrying said toothed wheels movably toward and away from said predetermined path of said sound film; magnetic cores mechanically connected with said axles of said toothed wheels; coils adapted to control said magnetic cores so as to move the teeth of said wheels into engagement with said sound film, when energized; means for selectively connecting said coils to a source of electric current; photoelectric means arranged along said predetermined film path after said toothed wheels so as to create electric current variations corresponding to variations of the pilot track produced by one of said toothed wheels; and means for varying the sound reproduced by said sound reproducing means in accordance with said electric current variations.

5. An arrangement for drawing on a previously developed sound film having a sound track at

least one pilot track comprising in combination means for transporting said sound film along a predetermined film path; means for reproducing the sound recorded by said sound track; a plurality of printing devices arranged along said predetermined film path and each having printing projections for printing different pilot tracks; means supporting said printing devices independently of each other and movable between inoperative position spaced from said predetermined film path and operative position moved toward said predetermined film path in engagement with a sound film passing along the same so as to be adapted to print a pilot track on the same; manually operable actuating means for selectively moving said printing devices from inoperative into operative position, whenever desired; photoelectric means arranged along said predetermined film path after said printing devices so as to create electric current variations corresponding to variations of said pilot track produced by one of said printing devices; and electrical means influenced by said electric current variations for varying the sound reproduced by said sound reproducing means in accordance with said electric current variations.

6. An arrangement for drawing on a previously developed sound film having a sound track at least one pilot track comprising in combination means for transporting said sound film along a predetermined path; sound reproducing means for reproducing the sound recorded by said sound track; at least one pilot track drawing member arranged along said predetermined path, means supporting said pilot track producing member movable between inoperative position spaced from said predetermined path and operative position moved toward said predetermined path in engagement with a sound film passing along the same so as to be adapted to draw a pilot track on the same, and manually operable actuating means for moving said pilot track producing member from inoperative into operative position whenever desired.
